UNITED STATES PATENT OFFICE.

WILLIAM H. SMYTH, OF BERKELEY, CALIFORNIA, ASSIGNOR TO HUMPHREY GAS
PUMP COMPANY, A CORPORATION OF NEW YORK.

INTERNALLY-FIRED ENGINE.

1,089,444.

Specification of Letters Patent. Patented Mar. 10, 1914.

Application filed February 5, 1900. Serial No. 4,129.

To all whom it may concern:

Be it known that I, WILLIAM H. SMYTH, mechanical engineer, citizen of the United States, residing at Berkeley, in the county 5 of Alameda and State of California, have invented certain new and useful Improvements in Internally-Fired Engines; and I do hereby declare the following to be a full, clear, and exact description of the same.

10 This invention relates to internally fired engines and has for its object, a more perfect utilization of the expansive force of heat and also simplicity of construction.

15 A further object of this invention is to provide an internally fired heat engine particularly adapted to raising or forcing water by the direct application of the expansive force of heat as displayed in explosive action.

20 These objects are accomplished by means of the device illustrated in the accompanying drawings in which:-

Figure 1 shows a sectional elevation, the upper part down to the joint line at the bottom of cylinder 7 being a section on the line A B C D of Fig. 4 and Fig. 5. From this joint line down, the balance of the figure is a section on line E F of Fig. 3 and Fig. 5. Fig. 2 is a sectional elevation through line 25 G H I J of Fig. 3 with cylinders 10 and 7 and cam 12 section on the line K L. Fig. 3 is a section through line M N of Figs. 1, 2 and 6. Fig. 4 is a plan view with the cover 30 removed. Fig. 5 is a full plan. Fig. 6 is a 30 front elevation. Fig. 7 shows an elevation of the device as placed in position in connection with the receiving tank, parts of the view being broken away to more clearly illustrate it.

35 Having now briefly described the figures I will for the sake of clearness describe each figure in detail and then by means of a full and detailed description of the operation make clear the function and coöperation of 40 the various parts.

Fig. 1 is a vertical section as stated. The view is not a section on a true plan as, for purposes of illustration, the upper part of the view is made to include more than 45 would be seen in a section made on a perfect plan, by this means the valve mechanism is made clearer. Referring to this figure, 1 is an explosive chamber or cylinder (using this term conventionally) of any suitable 50 form, the upper end of which constitutes a

pump chamber, the lower end of this cylinder is prolonged into a return curve or conduit 2, the outlet of which is provided with a check valve or gate 3 of large capacity opening outward, more particularly described hereinafter. A check valve 4 opening inward is provided preferably at the bottom of the return curve. A strainer 5 protects this valve. An air chamber or accumulator 6 surrounds and embraces the cylinders 65 1 of which there are two like that shown in this figure, located side by side, as shown in Figs. 2 and 3. Within this casing and depending from the upper end thereof is a large cylinder 7 having a movable piston 8 70 therein. It is provided with a port or passage 9 opening into and communicating with the cylinder 1 at its lower extremity, the passage from the upper portion of the cylinder 7 communicating with one cylinder 1, while 75 the passage from the lower part of cylinder 7 communicates with the other cylinder 1 at the corresponding location. These connections are indicated by the dotted lines connecting the upper and lower apertures 9 and 80 are shown in Figs. 1 and 3 at 9. Depending from the cylinder 7 is another cylinder 10 extending down into the air chamber 6. Depending from the upper portion of the cylinder 7 is a spiral or rifled bar 11 journaled 85 in the upper head of cylinder 7. To this bar 11 where it extends through the cylinder head, is secured a cam 12 upon the circumferential surface of which, are suitable contours to operate various valves and other directing and controlling mechanisms. The cylinder 1 is provided with an ignition chamber 13, in which is located a suitable ignition device shown in this figure as a rotatable 90 toothed wheel or star 14, forming one electrode of an electric circuit and an insulated spring 15 forming the other electrode. The battery and electric circuit are clearly shown in Fig. 4. The ignition chamber is provided with an inlet valve 16 suitably connected with a source of fuel supply, shown 95 in this instance as being a reservoir 17, having a suitable valve controlled pipe 18 provided with a regulating valve 19 and a stop cock 20. The valve 16 is provided with a 100 spring controlled stem, which engages with a suitably disposed contour on the surface of cam 12 to operate the valve in proper time. An exhaust valve 21 is also provided, similarly arranged and connected with a suit- 105 110

able cam contour on the cam 12, to give it appropriate motion.

The cylinder 10 is provided with a piston 22, shown in Figs. 2 and 3. This piston is operated by water pressure controlled by suitable valves, shown in Fig. 1 as piston 23 and auxiliary valve 24. Valve 24 is provided with a spring controlled stem, which engages with a suitable operating contour 10 on cam 12. A pressure supply pipe 25 extending downwardly into the lower part of the air chamber below the surface of the water therein connects through the valves 23 and 24 with the cylinder 10, to actuate the piston therein. It is supplied with a suitable stop cock 26, with an operating handle 27 extending to the outside of the machine for the purpose of stopping and starting its operation. Upon the stem of the valve 26 is secured a lever 28, see Fig. 4, connected by a link with the stop cock 26 of the fuel supply pipe, to open and close it synchronously with the operation of valve 26. 29 is an exhaust outlet for valve 23, shown, in the present case as extending to the outside of the machine. A cover or casting 30 covers and incloses the light working parts, which have been described. This cover may be hinged or otherwise removably secured in place. It is shown in the present instance as being bolted. For constructive purposes, the device is made in three main sections which are bolted, as shown in this figure, and also in Figs. 2, 4, 5 and 6.

Fig. 2 is a vertical section at right angles to Fig. 1 similarly modified for the purposes of clearer illustration. In some of the figures, including the present one, parts are omitted to avoid complication and obscurity in the views, these parts are however clearly shown in other views, also their connection and relation to the other parts of the machine. This view shows two cylinders, side by side, substantially similar to each other, and to that shown in Fig. 1, each provided with inlet and outlet valves, and a strainer common to both. The air chamber 6 is shown in this view, surrounding and inclosing the cylinders 1 and their valves 3, 3 as already described, as shown in Figs. 1 and 3. The walls of the air chamber form a smooth outer casing for the whole device. Within this casing and depending from the upper part thereof are shown the cylinders 7 and 10 in section and the pistons 8 and 22 already referred to. Connecting these pistons 8 and 22 is a hollow piston rod 31 closed at its lower end. Extending from the upper end of the upper cylinder, are two pipes 32 and 33 which form guides for the piston 8 and also prevent its axial turning. These pipes extend to the outside of the cylinder and form water passage ways, one to the upper and the other to the lower ends

respectively of the lower cylinder 10 as shown. They also connect with the controlling valve 23 as shown in Fig. 4. The spiral or rifled rod 11 is here shown extending centrally downward through piston 8 and entering the piston rod 31. At the upper end of this piston rod is a nut 34 secured to the piston 8, which engages with the spiral rod 11 to turn it by the longitudinal motion of the piston 8. The circular cam 12 is also here shown.

Extending upwardly through the air chamber to its upper part, is an air pipe 35, its upper end in open communication with the air chamber 6. The lower end of this pipe is furnished with a suitable controlling valve 36, opening into the cylinder 1 a little below valve 3. A valve stem extends to the outside of the casing through a suitable stuffing box and engages with the operative cam 12 in any suitable way to be operated thereby, shown in the present instance as a pivoted arm or lever, one end of which is loosely connected to the upper end of the valve stem and the other end engaging with cam 12, which is provided with an appropriate contour to depress the lever and raise the valve at proper times. A spring 37 raises the lever and assists in returning the valve to its seat after each operation. A similar valve, pipe and other described connections are supplied to the other cylinder 1, occupying a corresponding location in relation thereto, as shown in Fig. 3 at 35, which indicates cross sections of pipe 35 100 and valve stem.

The source of electric energy heretofore referred to with which the electrodes 14 and 15 connect, is here shown as cells of a battery 38. A chain 39 attached to a ring bolt 40 fixed to the cover 30, is provided for the purpose of suspending the apparatus, when it is required to be employed in situations where a permanent foundation is not available, or where such means for supporting, is for any reason desirable. The outlet is indicated in Fig. 2 by the dotted line 41. It is also shown as a pipe 41 in Fig. 1 and shown curved as a flexible pipe 41 in Fig. 6. Independent removable covers 42 are provided over the stuffing box of valve rod of valve 36, to permit of easy access to the stuffing box, or the removal of the valve 36 for the purpose of repair.

It is seen from Fig. 2, that each cylinder 1 is provided with an independent water inlet having an independent controlling valve 4, but that these valves are protected by a strainer or casing common to both.

Fig. 3 is a sectional plan through the body 125 of the air chamber, about midway of the length of the cylinder 10. It shows the cylinders 1 and their relation to each other, it also shows the valves 3; one of these valves being shown as partly 130

broken away for purpose of showing the character of the valve seat. These valves must be of extreme sensitiveness and they should be of very large capacity. This view shows the passages 9 leading from the top and bottom respectively of the cylinder 7, one to each of the cylinders 1 as heretofore described. This view also shows the location of the actuating pressure pin 35 and the pipe 33 leading to the lower end of the cylinder 10. It also shows the position of the various parts therein.

Fig. 4 shows a plan view of the machine, the protecting cap or cover 30 of the operative mechanism, being removed. It shows the casings 43 of the inlet and exhaust valves 16 and 21, with the exhaust outlets 44. It also shows the inlet pipe 45 for air or gas with its fuel stop cock 19 and its back flow check valves 46 and a link connecting the fuel stop cock with the operating lever of the valve stem of valve 26. It also shows how provision is made for connecting and controlling the electric current. Attached to the stem of valve 26 is a projecting finger 47. A stop 48 insulated from the machine is located in the path of the finger 47 so that when the valve is turned on it acts both as a stop, to limit the motion of the valve handle upon the stem of which it is secured and likewise to throw the battery into the electric circuit, ready to be completed by the engagement of the electrodes 14 and 15. The electrodes 15 insulated from the machine, are connected by the wire 49 to one pole of the battery 38, the other electrodes 14 being connected to the battery through the machine, finger 47, stop 48, when the finger engages therewith, and wire 50. Fig. 4 also shows the connection of valve stem of valve 35 and its connection with the central cam.

Fig. 5 is a plan of the machine showing the general appearance from this point of view. It shows the ring bolt 40, the exhaust outlets 44 the air inlet 60, the fuel reservoir 17 and stopping and starting handle 27. Fig. 5 also shows the protecting cover 30 of the operative mechanisms and the arrangement of the bolts securing this cover in place and also those which connect the main body of the machine together.

Fig. 6 is a front elevation of the machine in position. It shows its general arrangement and outward appearance and the manner in which the discharge pipe is attached to the discharge outlet. The discharge pipe is shown as a flexible hose appropriate to the location in which the device is represented. It also shows the proper immersion of the device, though this is a matter which may be varied considerably without materially affecting its efficiency. Fig. 7 shows an elevation of one of these devices to raise water in a tank with automatic arrangements

whereby a definite rise and fall of the water in the tank operates the starting and stopping handle 27. This consists of two floats 61 and 62 suspended in the tank from a rocking counter-weighted lever 63 connected by a rod to a bellcrank lever 64 which is connected by a link to the operating handle 27 as indicated in this view. This construction provides that when the water level falls in the tank, the device starts in operation and fills the tank till the water reaches the upper float when it reverses and closes the valve 26. It requires the aggregate buoyancy of both floats to move the valve in one direction and the aggregate weight of both floats to move it in the other direction.

Owing to the extreme velocity with which the water passes through valve 3 and the extreme suddenness with which the reaction from pressure to vacuum takes place, it is necessary as before stated, that the valves 3 should be of great sensitiveness to prevent loss by slippage, that is to say, the return of the water through the valve before its inertia prevents of its closing. It should also be of great capacity to avoid friction and hesitation of water in passing through.

The operation of the device is as follows: Assuming the parts of the machine to be in position as indicated in Fig. 1 and the discharge pipe extending to some elevation and the device furnished with a body of water filling the pump cylinders or chambers 1, to act as pistons, other water in the discharge pipe and air in the air chamber under the pressure of the head to which the device is intended to raise water. The liquid fuel valve 19 being opened to the proper extent to give correct supply of fuel, the device is ready to start. This is accomplished by turning the handle 27 shown in Figs. 1, 5 and 6. This opens valve 26 shown in Fig. 1 and Fig. 4. This valve 26 controls the supply of water from pipe 25 extending the length of the air chamber 6 to near the bottom and beneath the surface of the water in the air chamber 6 which water is under the pressure of the head as the discharge 110 valve 41 is in free communication with the air chamber 6. Thus the resiliency of the air 115 in the air chamber 6 forces the water from said air chamber up pipe 25 through the now open valve 26 into the chamber containing the controlling valve 24 and the water thus admitted forces the piston valve 23 from the position shown in Fig. 1 to the opposite 120 end of the chamber in which the piston valve 23 is located, thus changing the course 125 of the water, under pressure of the air chamber coming through pipe 25, from pipe 32 as shown in Fig. 4 to the pipe 33 as shown in Figs. 2 and 4. It will be seen that while the pipes 32 and 33 extend down through cylinder 7, the pipe 32 opens into the upper part of the cylinder 10 while the 130

pipe 33 continues downward and extends to and opens into the bottom end of the cylinder 10 beneath piston 22. The opening of valve 26 has brought the pressure of the head to which the water is being forced, upon the underside of piston 22 through pipe 25, valve 26, chamber of valve 24 and the port connecting with the pipe 33 in the chamber of valve 23. Thus under the pressure of the head or what is equivalent thereto, the resilient force of the air in the air chamber 6 compressed by the weight of the head of the water, the piston 22 is caused to rise moving with it the piston 8 in cylinder 7, to which it is rigidly connected by the hollow piston rod 31. The water above the piston 22 in cylinder 10 being forced outward through pipe 32 of Figs. 2 and 4 through chamber of valve 23 and exhaust passage 29 shown in Fig. 1.

The effect of the upward movement of piston 8 is to force the water from the top of cylinder 7 as shown in Fig. 1 through passage 9 of the same figure down the whole length of the machine to the opening 9 beneath valve 3 and consequently into cylinder 1 of Fig. 1, thus filling the vacant space shown in Fig. 1 and marked 1, thus forcing out the spent gases of previous charge through the ignition chamber 13 and exhaust valve 21 which has been meanwhile opened by the cam 12 and thence out through the exhaust passage 44, one of which is shown in Fig. 1. In the meantime the rising of piston 8 has performed the reverse operation for the companion cylinder 1, from which has been drawn by suction, that is forced by atmospheric pressure, a like volume of water to fill the space beneath piston 8 made by its upward movement. The lower part of cylinder 7 as above stated, is connected by a similar passage 9, to the lower part of the companion cylinder 1. These passages 9 which connect the upper and lower part of cylinder 7 are shown in Fig. 3 as incased in the wall of air chamber 6. It will thus be seen that while the uprising of piston 8 has introduced a measured volume of water into one of the cylinders 1, and thus forced out the spent gases, it has simultaneously caused the withdrawal of a similar volume of water from the companion cylinder 1 and the consequent entrance of air through the inlet valve 16, which has meanwhile been opened for that purpose. The opening and closing of these valves is performed automatically by the contour of the circular cam 12 shown in Figs. 1 and 4. The valves, both inlet and exhaust, of the companion cylinders 1 are similar and in duplicate, as are also the sparking devices. The valves and sparking devices are shown in Fig. 1, and the casing containing them is shown in Fig. 4. The operation of these valves in proper

time is performed by the cam 12 actuated by the rifled rod 11 engaging with the nut or other suitable engagement 34 of piston 8 shown in Fig. 2.

The turning of handle 27 besides opening the valve 26 and causing the actuation of piston 8 as described also turns the finger 47 attached on the same valve stem as the handle 27 into engagement with the insulated stop 48. This engagement besides limiting the motion of the valve handle completes the electric circuit from the battery to the sparking star 14 through the machine. The motion of handle 27 besides performing these two functions opens the stop cock 20 of the fuel supply. The fuel, preferably gasolene, drips down into the up turned elbow of pipe 45, Fig. 4, through which the air passes to supply the space in cylinder 1, as water is withdrawn therefrom by the motion of piston 8. That is to say air, with its complement of gasolene will flow past the check valve 46 of the cylinder from which water is being withdrawn. It may now be assumed that one of the cylinders 1 is filled with gasolene impregnated air, that is gasolene vapor at atmospheric pressure, and the piston 8 has nearly reached one end of its stroke.

The next operation after the closing of exhaust valve 21 and inlet valve 16, is the opening of valve 36, by the engagement of its lever with cam 12, thus through the holes at the top of the pipe 35 shown in Fig. 2 and Fig. 3, the compressed air in the air chamber or accumulator 6, is permitted to flow, through pipe 35 beneath valve 3 of the cylinder 1 which has received its charge of explosive mixture. Assuming this is the condition shown in Fig. 1, that is, that it has its charge of gas at atmospheric pressure, the water beneath valve 3 would be displaced by a volume of air from the air chamber and the water in chamber 1 would be forced upward by this displacement and so compress the inclosed explosive charge by the upward movement of the surface of water beneath the explosive charge. The device is now in condition of having in one of the cylinders 1, a charge of explosive gases compressed to a degree of compression equal to the static head to which the water is being raised, while the other cylinder is filled with water which has forced out the previously exploded charge. The further motion of the piston 8 and cam 12 slightly rotates the star 14 which, as already described, is in the electric circuit with the battery, into wiping engagement with the spring 15 which is constantly in the electric circuit, thus producing a spark which ignites and explodes the compressed charge.

The last motion of piston 8 and cam 12 is to reverse the position of small piston valve 24 which in its turn diverts the water

pressure to the opposite end of the valve 23 which being moved thereby in its turn diverts the course of the water from pipe 33 to pipe 32 and the top end of cylinder 10 and consequently causes the downward motion of piston 22 and thus a repetition of the described operation with reference to the cylinder 1 which we left full of water and so on in indefinite cycle the 10 continuous operation of the machine. Of course the explosion and expansion of the compressed charge creates the partial vacuum in the cylinder 1 in which it occurs and this is satisfied with water through the foot 15 valve 4 of the cylinder in which the vacuum exists.

The fuel is preferably carried in a reservoir on the top of the device as shown in Fig. 1 at 17. This reservoir is provided 20 with a simple plug or other suitable regulating valve shown in Fig. 1 at 19 on its pipe 18 for the purpose of regulating the amount of flow of the gasoline. The pipe 18 projects downward into the open end 25 of the upturned pipe 45 shown in Fig. 4 which is the air supply pipe common to both cylinders 1. This pipe 45 branches in opposite directions to the valve chest of each cylinder 1 and may be provided on each 30 of its branches with an inlet check valve 46. These check valves are not ordinarily necessary but are simply additional precaution, as the valve 16 to the chamber back of 35 which pipe 45 leads, as shown in Fig. 1, is sufficient to cut off the explosive flame from the pipe 45. The valve 16 is a positively operated valve whereby attenuation of the charges is prevented. After the explosion 40 has occurred the spent gases are simply forced out through the ignition chamber 13, exhaust valve 21 and outlet 44 as shown in Figs. 1, 4 and 5. The hole 60 as shown 45 on the cover in Fig. 5 is purposely not in close proximity to the air and fuel pipe 45 but is at some considerable distance away, the object of this being to have a current of 50 fresh air flowing through the whole chamber beneath the cover so as to sweep out any gasoline vapors which might accumulate there.

The electric circuit is clearly shown in Fig. 4, the wire 49 connecting one pole of the battery 55 38 with the insulated posts to which the insulated springs 15 are attached as shown in Figs. 1 and 4. The other wire 50 connects the other pole of the battery with the insulated stop post 48, into contact with which the finger 47 is brought by movement of the handle 27 as already described. This makes 60 connection with the sparkler star 14 through the metal of the machine. The automatic starting and stopping arrangement may or may not be used as the circumstances warrant. Its method of operation is obvious 65 from the description.

It will be observed in this form of the invention that prior to and during heat generation, the explosion chamber is not only surrounded on the inside by a film of non-conducting material of much less conductivity, (namely a film of water) than the material of the cylinder, but that on the outside it is likewise covered and encompassed by a non-conductor namely, air. Further that immediately succeeding the heat generation, the cylinder is cooled by the rush and splash of the water into the air chamber insuring a complete cooling of the cylinder walls prior to the inflow of a succeeding charge. Also that whatever heating may 70 take place of the cylinder walls during the generation of heat, it is transferred to the air in the air chamber with its consequent heating of the air therein and its transformation into available work. These functions, though of course not so valuable in the present device, as they would be if available in the previous types of heat energy utilizing devices, are here incorporated for what 75 they are worth.

It is obvious of course, that though, for the purposes of constructive economy, the whole of the heat generation or explosion chamber is not inclosed within the air chamber, that this may readily be accomplished 80 if deemed desirable.

It is also apparent that the charging and pressure cylinders are not of necessity located within the air chamber or even inherently and of necessity intimately connected with the air chamber. They may be located at a considerable distance from the explosion chamber, as for example on the surface of the ground in cases where it is desirable to have the explosion chamber at the bottom of 90 a shaft or well.

It is also apparent that the whole device itself may be located at a distance from the point at which the work is being utilized, as for instance, the air, water or impulses may 100 be carried by air or water pipes or other means to suitable devices at the bottom of a shaft or other distant location, while the device itself remains at the surface or other position separated from such force utilizing 105 devices.

Besides the various forms or modifications herein illustrated, described or referred to this invention is capable of great variation of form, arrangement and constructive detail without departing from the essential nature of the invention, some of such being possibly more satisfactory embodiments of the invention than these illustrated in the present disclosure.

An illustration of another embodiment of the invention involved in the present disclosure differing radically in appearance and constructive detail, is presented in the companion application for improvements in 110 115 120 125 130

utilizing heat energy filed Feb. 5th, 1900,
Serial No. 4128.

As illustrating the extent and scope of the invention underlying the construction herein set forth reference is here made to another accompanying application also filed on the same day bearing Serial No. 4127 for a new art or process under the title of improvements in utilizing heat energy.

10 It will be seen that many changes in form, construction and arrangement of the various parts of this device also means employed in charging the explosion chamber with power and of causing the explosive force of heat 15 to be exerted against the piston may be made to apply this invention without departing from the essential character thereof. I do not therefore confine myself to the form proportion or arrangement of the devices or 20 any of them herein shown, but merely show this as a convenient form in which the invention may be applied to a large number of uses.

What I claim is:—

25 1. In an apparatus of the named type, the combination of a combustion chamber provided with an igniter and means to regulate the in and outflow of fluids, an air chamber surrounding the combustion chamber and having an inlet passage thereto and a discharge from the air chamber.

30 2. In an apparatus of the named type, the combination of a combustion chamber provided with an igniter and means to regulate the in and outflow of fluids, an air chamber surrounding the combustion chamber and having a valve controlled inlet passage thereto and a discharge from the air chamber.

35 3. In an apparatus of the named type, the combination of a multiplicity of combustion chambers provided with suitable devices and having controlling devices to regulate the in and outflow of fluids, an air 40 chamber surrounding the combustion chambers connected therewith by suitable passages, a discharge from the air chamber, means adapted to form a succession of explosive charges and a power driven engine 45 to introduce the charges into the combustion chamber.

45 4. In an apparatus of the named type, the combination of a combustion chamber provided with an igniter and means to regulate the in and outflow of fluids, an air chamber surrounding the combustion chamber, an inlet passage from the air chamber to the combustion chamber whereby material driven from the combustion chamber 50 is opposed by the air in the air chamber and a discharge from the air chamber.

55 5. In an apparatus of the named type, the combination of a combustion chamber provided with an igniter and means to regulate the in and outflow of fluids, an air

chamber surrounding the combustion chamber, means to introduce liquid to act as a piston in the combustion chamber, a valve controlled inlet passage from the air chamber to the combustion chamber whereby liquid driven from the combustion chamber is opposed by the air in the air chamber and a discharge from the air chamber. 70

6. In an apparatus of the named type, the combination of a combustion chamber 75 provided with an igniter and means to regulate the in and outflow of fluids, a non-return valve controlled passage to introduce liquid from the exterior to act as a piston in the combustion chamber, an air chamber 80 surrounding the combustion chamber, a valved controlled inlet passage from the air chamber to the combustion chamber whereby liquid driven from the combustion chamber is opposed by the air in the air chamber 85 and a discharge from the air chamber.

7. In an apparatus of the named type, the combination of a combustion chamber provided with an igniter and means to form a succession of explosive charges, a power 90 driven engine or motor to introduce the charges into the combustion chamber, a non-return-valve controlled passage to introduce liquid from the exterior to act as a piston in the combustion chamber, an air chamber 95 surrounding the combustion chamber, a valve controlled inlet passage from the air chamber to the combustion chamber whereby liquid driven from the combustion chamber is opposed by the air in the air chamber, 100 and a discharge from the air chamber.

8. In an apparatus of the named type, the combination of a multiplicity of combustion chambers with suitable igniters and means to form a succession of explosive 105 charges, a power driven engine or motor to introduce charges into the combustion chambers, a non-return-valve controlled passage to introduce liquid from the exterior to act as a piston in each of the combustion chambers, an air chamber surrounding the combustion chambers, a valve controlled passage connecting each of the combustion chambers with the air chamber whereby liquid driven from the combustion chambers is opposed by the air in the air chamber, and a discharge from the air chamber. 110

9. In an apparatus of the named type, the combination of a combustion chamber provided with an igniter and means to regulate the in and outflow of fluids, an air chamber surrounding the combustion chamber connected therewith by a passage, a second passage or passby between the air chamber and the combustion chamber, and a discharge from the air chamber. 115 120

10. In an apparatus of the named type, the combination of a combustion chamber provided with an igniter and means to regulate the in and outflow of fluids, an air 125

chamber surrounding the combustion chamber connected therewith by a valve controlled passage, a second valve controlled passage or passby between the air chamber 5 and the combustion chamber, and a discharge from the air chamber.

11. In an apparatus of the named type, the combination of a multiplicity of combustion chambers provided with suitable 10 igniting devices, means to form a succession of explosive charges, means to introduce charges into the combustion chambers, an air chamber surrounding the combustion chambers and connected to each of said 15 chambers by valve controlled passages and a discharge from the air chamber.

12. In an apparatus of the named type, the combination of a combustion chamber provided with a vaporizer or gasifier of 20 liquid fuel, means for introducing the fuel and a succession of volumes of air to form explosive charges in a combustion chamber, an igniter, means to regulate and direct the in and outflow of fluids, an air chamber surrounding the combustion chamber and having 25 an inlet passage thereto, and a discharge from the air chamber.

13. In an apparatus of the named type, the combination of a combustion chamber 30 provided with a vaporizer or gasifier of liquid fuel, an engine for introducing the fuel and a succession of volumes of air to form explosive charges in the combustion chamber, an igniter, means to regulate and direct 35 the in and outflow of fluids connected therewith by a passage, an air chamber surrounding the combustion chamber, and a discharge from the air chamber.

14. In an apparatus of the named type, 40 the combination of a combustion chamber provided with an igniter and means to form and introduce into the combustion chamber a succession of explosive charges, means to compress the charges prior to ignition, 45 means to permit and direct the flow of fluids into and from the combustion chamber, an air chamber surrounding the combustion chamber and having an inlet passage thereto and a discharge from the air chamber.

50 15. In an apparatus of the named type, the combination of a combustion chamber provided with an igniter and means to form and introduce into the combustion chamber a succession of explosive charges, means to 55 permit and direct the flow of fluids into and from the combustion chamber, an air chamber surrounding the combustion chamber connected therewith by a passage, a bypass or passage from the air chamber to the combustion chamber to effect the compression of the charge, and a discharge from the air chamber.

16. In an apparatus of the named type, the combination of a combustion chamber 60 65 provided with a vaporizer or gasifier of liq-

uid fuel, means for introducing the fuel and a succession of volumes of air to form explosive charges in the combustion chamber, means to generate electrical energy, a sparkler to ignite the charges, means to permit and direct the flow of fluids into and from the combustion chamber, an air chamber surrounding the combustion chamber, and having an inlet passage thereto, and a discharge from the air chamber. 70 75

17. In an apparatus of the named type, the combination of a combustion chamber, means for introducing fuel thereinto, a pump or the like to introduce a succession of volumes of air to form with the fuel explosive charges in the combustion chamber, an igniter, means to permit and direct the flow of fluids into and from the combustion chamber, an air chamber surrounding the combustion chamber and having an inlet passage thereto and a discharge from the air chamber. 80 85

18. In an apparatus of the named type, the combination of a combustion chamber provided with an igniter and having valves 90 to permit and direct the introduction of explosive charges, an engine or motor to effect the introduction of the charges and connected to the valves and sparkler by suitable mechanical devices to effect their appropriate motions in operative sequence, means to permit and direct the flow of fluids into and from the combustion chamber, an air chamber surrounding the combustion chamber and having an inlet passage thereto, and a discharge from the air chamber. 95 100

19. In an apparatus of the named type, the combination of a combustion chamber, means to permit and direct the flow of fluids into and from the combustion chamber, a surrounding and inclosing casing forming an air chamber having an inlet passage to the combustion chamber and a discharge from the casing, means for introducing into the combustion chamber a succession of explosive charges and igniting them. 105 110

20. In an apparatus of the named type, the combination of a combustion chamber, means to permit and direct the flow of fluids 115 into and from the combustion chamber, a surrounding and inclosing casing forming an air chamber having a valve controlled inlet passage to the combustion chamber and a discharge from the casing, means for 120 introducing into the combustion chamber a succession of explosive charges and igniting them.

21. In an apparatus of the named type, the combination of a plurality of combustion chambers provided with suitable 125 igniters and means to regulate the in and outflow of fluids, an air chamber surrounding the combustion chambers having inlet passages thereto, and said combustion chamber 130

bers having inlet passages to the air chamber, and a discharge from the air chamber.

22. In an apparatus of the named type, the combination of a multiplicity of combustion chambers provided with automatic motor means to introduce a succession of explosive charges and ignite them, devices to control the flow of fluids into and from said chambers, an air chamber surrounding the combustion chambers connected therewith by passages, and a discharge from the air chamber.

23. In an apparatus of the named type, the combination of a multiplicity of combustion chambers with automatic motor means to introduce a succession of explosive charges and ignite them, devices to control the flow of fluids into and from said chambers, an air chamber surrounding the combustion chambers connected therewith by valve controlled passages, and a discharge from the air chamber.

24. In an apparatus of the named type, the combination of a multiplicity of combustion chambers with igniters and means to control the inflow and outflow of fluids, an air chamber surrounding the combustion chambers connected therewith by passages, a discharge from the air chamber, and automatic means to form and introduce a succession of explosive charges into each of the combustion chambers.

25. In an apparatus of the named type, the combination of a combustion chamber, automatic means for introducing and igniting therein a succession of explosive charges, fluid means for accumulating the

power derived from the ignited charges and means for stopping and starting the apparatus automatically by fluctuations of the power accumulating means.

26. In an apparatus of the named type, the combination of a combustion chamber, automatic means for introducing and igniting therein a succession of explosive charges, means for permitting and directing the flow of liquid into and from the combustion chamber, a tank or receptacle for liquid expelled from the combustion chamber, and means for automatically stopping and starting the apparatus by fluctuations in the level of the liquid in the receptacle.

27. The combination of a pump chamber, an accumulator, a conduit for the reciprocation of liquid connecting the pump chamber with the accumulator, a discharge outlet and a liquid inlet, and means for utilizing the pressure of the accumulator for causing a return movement of liquid in the conduit and pump chamber.

28. The combination of a pump chamber, an accumulator, a conduit for the reciprocation of liquid connecting the pump chamber with the accumulator, a liquid inlet and a discharge in the vicinity of the inlet, and means for utilizing the pressure of the accumulator for causing a return movement of liquid in the conduit and pump chamber.
